[57] CLAIM

The ornamental design for the runner's hand grip, as
shown and described.

DESCRIPTION

FIG. 1 is a perspective view of a runner's hand grip
showing my new design;

FIG. 2 is a side elevational view thereof;

FIG. 3 is a bottom plan view thereof;

FIG. 4 is an end elevational view thereof;

FIG. 5 is a perspective view of a modified form of the
design shown in FIGS. 1 through 4;

FIG. 6 is a side elevational view thereof;

FIG. 7 is a bottom plan view thereof; and

FIG. 8 is an end elevational view thereof.
